UNITED STATES PATENT OFFICE.

EDWARD JOSEPH ERICSSON, OF SAN FRANCISCO, CALIFORNIA.

AIR-SIGNAL VALVE.

1,133,116.

Specification of Letters Patent.

Patented Mar. 23, 1915.

Application filed October 21, 1914. Serial No. 867,754.

To all whom it may concern:

Be it known that I, EDWARD J. ERICSSON, a citizen of the United States, and a resident of San Francisco, in the county of San Francisco and State of California, have invented certain new and useful Improvements in Air-Signal Valves, of which the following is a specification.

My invention relates to signals actuated by air under pressure, as on railway trains, and the main object thereof is to provide a valve in the train signal air line which permits the actuation of a signal when a relief valve at any one of a plurality of points is opened, said signal preferably being in close proximity to a locomotive engineer or to a motorman of a motor car or train.

A further object is to provide such a valve which prevents the signal actuation when the train line is closed, regardless of the pressure of air in said train line.

A further object is to provide such a valve which permits the actuation of the signal by a portion of the air rushing from the air reservoir to an open relief valve; and further objects are to provide such valves which are simple in construction and installation, positive in action, well adapted for the purpose for which they are intended, and comparatively inexpensive.

My invention is fully described in the following specification, of which the accompanying drawings form a part, in which the separate parts are designated by the same reference characters in each of the views, and in which:

Figure 1 is a diagrammatic view of the train signal air line system, illustrated for two cars, provided with my valve; and Fig. 2 is an enlarged, detached, sectional, view of the valve, with a signal connected therewith.

In Fig. 1 I have illustrated the train line at 3, having the usual flexible couplings 4 between cars, and stop-cocks 5, said train line being in communication with a reservoir 6 for the compressed air and which, as shown, is the main reservoir also in communication with the air-brake system by means of a pipe 7, an air strainer 8 and reducing valve 9 being illustrated in connection with the portion 3^a of the train line pipe.

Within each unit of a train is a branch pipe 10 having a stop-cock 11 therein and a

relief valve 12 at the end thereof, the handles or levers of which relief valves are connected with suitable cords whereby the said valves may be actuated from any portion of the length of a train unit, the illustration being for a motor car with a trailer and the motor car being equipped with a relief valve whereby the conductor may signal the motorman whenever he so desires, but steam locomotives need not be so equipped.

Within the engineer's or motorman's cab is a whistle 13 connected by means of a pipe 14 with the lower portion of my valve 15, preferably by means of a threaded plug 16 having a bore 17 therethrough and provided with a reduced portion 18 at the upper end thereof, Fig. 2, and the upper end of said portion 18 is of conical formation, as shown. The plug 16 is threaded into a T-coupling 19, in one end thereof, and in the other end is a section of casing 20 also screw threaded into a similar coupling 21 in the other end of which is an air-tight plug 22 having a downwardly directed rod or bolt 23 adjustable therein, the train line pipe 3 being detachably connected with the coupling 21 and the reservoir pipe 3^a being similarly connected with the coupling 19.

Within the casing 20 is a freely movable slide valve 24 having upper and lower flanges 25 and 26, respectively, in close proximity to the inner walls of said casing 20 and provided with a relatively large bore 27 in the lower end thereof, the inner end of which bore is tapered to conform to the conical formation of the reduced portion 18 of the plug 16, to form a seat therefor, and I also provide small openings 28 in the sides of said bored end of the valve 24 to permit the entry of air thereto.

When a relief valve 12 is opened, in any of the units of the train, the air rushes therefrom because of the pressure in the reservoir 6, the flow of said air being through the portion 3^a of the train line, casing 20 of my valve 15, train line pipe 100 3, and branch 10, and, because of the flanges 25 and 26, the valve 24 is raised from its seat, and a portion of the air under pressure passes to and through the plug 16 and to the whistle 13, actuating the same, and notifying the engineer or motorman, but it will be noted that the flanges 25 and 26 do not prevent the free flow of air through the

22
 casing 20, being only of sufficient relative diameter to insure the raising of the valve 24 from its seat. When the relief valve is again closed, the air in the train line is held against escape, and under pressure, the pressure being the same throughout the train line and, thus, equal on both sides of my valve 15, and the signal is not actuated for this reason no matter what the air pressure may be, my valve continuously holding the signal out of communication with the train line signal pipe. It will also be noted that, while I may connect the train line signal pipe with the main reservoir, it has no connection whatever with the train line pipe system of the air-brakes, such as to effect the latter, the amount of air required to actuate the signal being inappreciable with respect to the pressure of the air holding the brakes out of operative position, the reducing valve 9 controlling the relative air pressures.

My invention is very simple, though highly efficient, is composed of few parts 25 and of which but one is movable, may be quickly installed in any desired arrangement of pipes, and is inexpensive, and, for the most part, the parts are what is known as "stock" and, therefore, readily repaired or replaced in the event of breakage, as in 30 collisions, etc.

Having fully described my invention,

Copies of this patent may be obtained for five cents each, by addressing the "Commissioner of Patents, Washington, D. C."

what I claim as new, and desire to secure by Letters Patent, is:—

1. The combination with pipes containing air under pressure, of a casing joining said pipes, a plug in one end thereof having a tubular extension and a bore therethrough, a weighted valve provided with a tubular portion encompassing said tubular extension and provided with air ports in the side thereof, said valve being provided with a flange of less diameter than the interior of said casing, and a whistle in communication with said plug bore. 35

2. The combination with pipes containing air under pressure, of a casing joining said pipes, a plug in one end thereof having a tubular extension and a bore therethrough, a weighted valve having a flange 50 thereon and provided with a tubular portion encompassing said tubular extension and provided with air ports in the side thereof, a whistle in communication with said plug bore, and means for limiting the 55 upward movement of said valve.

In testimony whereof I have signed my name to this specification in the presence of two subscribing witnesses.

EDWARD JOSEPH ERICSSON.
